UNITED STATES PATENT OFFICE.

WILLIAM G. JOPSON, OF WILLIAMSPORT, PENNSYLVANIA, ASSIGNOR TO C. A. REED COMPANY, OF WILLIAMSPORT, PENNSYLVANIA, A CORPORATION OF DELAWARE.

DECORATIVE WREATH.

Application filed July 12, 1927. Serial No. 205,194.

This invention relates to decorative objects made principally of paper or similar material which may for example take the form of a wreath. An object of the invention is to provide a decorative object such as a wreath which is capable of being made in a plurality of colors, which has an attractive appearance, and which is durable and shape retaining.

Various advantageous features of my invention will be apparent from the disclosure thereof in the following description and on the drawing, of which,—

Figure 1 represents in elevation a wreath embodying my invention.

Figure 2 shows a portion of the wreath in the course of construction.

Figure 3 is a section on the line 3—3 of Figure 2.

Figure 4 is an elevation of a portion of the wreath showing a means of securing the ends of the core together.

Figure 5 is a view of the ends of the core showing the fastening means therefor in section.

Referring to the drawing in detail, 10 represents a wire or other similar semi-rigid strand material which may be suitable for use as a core. The strand 10 is preferably of considerable strength and also somewhat springy in order to preserve the shape of the finished article against distortion. Upon the core 10 is threaded a strip 11 of paper or other sheet material or fabric having requisite shape-retaining qualities, crepe or plain paper or relatively stiff cloth being suitable for the purpose. The strip 11 prior to being threaded on to the core 10 is preferably wrinkled transversely into a series of

successive waves. These waves provide wavy or irregular edges 12 to the strip, which edges eventually constitute the outer surface of the finished product. The strip 11 is threaded on the core 10 in such a way that the latter passes through the center line of the strip alternately from one side to the other, preferably at short intervals. In the construction illustrated on the drawing, the core 10 passes through the strip 11 between each trough and crest of the waves or wrinkles formed therein. The strip thus threaded on to the core is twisted as indicated in Figure 2 so that the edges 12 follow helical paths. The turns of the strip about the wire are then pushed together as shown

in the left hand portion of Figure 2 so that the successive turns are contiguous. This forms a substantially continuous body of sheet material about the core 10 presenting a pleasing rough appearance. By threading desired lengths of different colored material successively on the core 10, bands of color may be formed in the finished article as desired. After the core has been filled by contiguous turns of the strip 11, the ends 65 may be sprung around to meet each other, thus forming a ring of the core and material arranged toroidally thereon. The ends of the core may be secured together in any preferred manner. As shown, I provide a sleeve 13 of metal or any other suitable material having a longitudinal bore 14 of a size to receive the ends of the wire 10 in a close fit. After inserting the ends of the wire into the bore 14, they may be secured therein as by crimping or indenting the sleeve 13 as at 15. The end portions of the strip 11 may then be worked over the sleeve 13 as shown in Figure 5 to cover the same and to present a wreath with an unbroken surface.

Having thus described an embodiment of this invention, it should be evident to those skilled in the art that various changes and modifications may be made therein without departing from its spirit or scope as defined by the appended claims.

I claim:—

1. An ornamental figure comprising a semi-rigid core and a strip of sheet material 90 twisted therearound, said strip having a series of transverse waves therein forming wavy edges, and presenting both its edges to define the surface of the figure.

2. An ornamental figure comprising an 95 elongated strip of transversely waved paper, and a semi-rigid core member threaded through said strip alternately from one face to the other and extending longitudinally thereof, said strip being twisted about said core member and presenting wavy edges to define the surface of the figure.

3. A wreath comprising a circular core member, and a toroidal body member surrounding the core, said body member comprising a transversely waved strip of sheet material twisted about the core and presenting its edges to define the surface of the wreath.

4. A wreath comprising a length of wire 110

bent into circular shape, and having its ends secured together, and a strip of paper threaded along its median line on said wire and twisted therearound, said strip having wavy edges defining the surface of the wreath.

5. A wreath comprising a length of wire bent into circular shape, and having its ends secured together, and a plurality of strips

of paper of various colors successively 10 threaded along their median line on said wire and twisted therearound, said strips having wavy edges defining the surface of the wreath.

In testimony whereof I have affixed my 15 signature.

WILLIAM G. JOPSON.
